UNITED STATES PATENT OFFICE.

MYLER J. SMITH, OF REDFORD, MICHIGAN.

VALVE FOR INTERNAL-COMBUSTION ENGINES.

Application filed October 15, 1923. Serial No. 668,585.

To all whom it may concern:

Be it known that I, MYLER J. SMITH, a citizen of the United States, residing at Redford, in the county of Wayne and State 5 of Michigan, have invented a new and useful Valve for Internal-Combustion Engines, of which the following is a specification.

This invention relates to valves and particularly to tappet valves for internal combustion engines.

It is the object of the invention to effect a gradual rotative creeping of the valves upon their seats when an engine of the specified character is in operation, utilizing the 15 recurrent changes of pressure upon the top faces of the valves to effect such a movement, whereby a continuous automatic grinding of the valves to their seats is accomplished and any carbon lodging upon the valve seats 20 or seating surface of the valves is at once removed.

In attaining this object, the invention contemplates providing upon the top faces of the valves a series of approximately radial 25 vanes of such form that rotative impulses in one direction will be imparted to the valves by the sudden increases of gaseous pressure acting against said vanes during the explosion and compression strokes.

A preferred embodiment of the invention is hereinafter described, and is illustrated in the accompanying drawing, wherein,

Fig. 1 is a side view of the improved valve indicating in dash lines the seat-forming 35 portion of an engine valve.

Fig. 2 is a view of the valve in sectional elevation.

Fig. 3 is a top view of the valve.

In these views the reference character 1 40 designates a tappet valve and 2 the stem thereof, the general form of said valve being that which is in common use for controlling the intake and exhaust ports of internal combustion engines. The present invention 45 consists in forming upon the outer face of such a valve (that is to say, the face remote from the stem 2) a series of approximately radial vanes 3, each having a triangular cross-section with one face 4 perpendicular 50 to the top surface of the valve, and another face 5 inclined to said surface preferably at

an approximate angle of forty-five degrees. A more effective response to increases of pressure is found to result from giving the vanes 3 an arcuate rather than a strictly 55 radial form. Said vanes are extended outwardly to the periphery of the valve, and at their inner ends terminate a short distance from the valve center.

When said vanes are properly proportioned, each increase of gaseous pressure, resulting either from explosion or compression of the mixture in the cylinder controlled by the valve, creates a momentary unbalanced pressure upon the faces 4 and 5 of the 60 valve resulting in a slight rotative advance of the valve upon its seat in the direction of the arrow (see Fig. 3). This momentary lack of balance between the pressure on the vane faces 4 and 5 follows from the fact that 65 pressure acting perpendicularly upon the top face of the valve has a circumferential component, as applied to the inclined faces 5, while such pressure is not effective upon the faces 4, since the latter are parallel to 70 the direction of such pressure. This condition of unbalanced pressure exists only at the moment of the initial sudden rise of such pressure, and consequently the rotative response of the valve to each explosion or 75 compression is quite slight. This frequently recurring slight advance is sufficient, however, to secure the desired grinding effect, thus eliminating the periodic manual grinding which is required by such valves as have 80 heretofore been employed.

What I claim is:

1. A tappet valve having a plurality of approximately radial vanes upon its top surface, each of said vanes having opposite 90 faces, one of which is perpendicular to said surface and the other inclined at an acute angle to said surface.

2. The method of insuring proper seating of an internal combustion engine valve comprising intermittently and gradually rotating the valve by fluid pressure while the valve is fully seated, during operation of the engine.

3. The method of insuring proper seating 100 of an internal combustion engine valve consisting in utilizing pressure of the gas con-

trolled by said valve to effect a gradual rotative actuation of the valve while fully seated during operation of the engine.

4. The combination with an internal combustion engine valve chamber, of a valve comprising a stem and a head terminally carried by said stem, said head seating within said chamber and having a plurality of

faces upon its outer surface and within said chamber extending substantially radially inward from the rim of said valve and inclined at an acute angle to the valve axis.

In testimony whereof I sign this specification.

MYLER J. SMITH.
